UNITED STATES PATENT OFFICE.

WILLIAM S. BALES, OF KOPPERL, TEXAS.

SELF-DUMPING DRAG-HARROW.

1,156,968.

Specification of Letters Patent. Patented Oct. 19, 1915.

Application filed September 27, 1913. Serial No. 792,154.

To all whom it may concern:

Be it known that I, WILLIAM S. BALES, a citizen of the United States of America, residing at Kopperl, in the county of Bosque and State of Texas, have invented certain new and useful Improvements in Self-Dumping Drag-Harrows, of which the following is a specification, reference being had therein to the accompanying drawing.

10 This invention relates to harrows, and has for its object the production of a simple and efficient harrow which is constructed of a minimum number of parts and which may, therefore, be manufactured at a minimum

15 cost. Another object of this invention is the production of a simple and efficient means for elevating the harrow and turning the teeth of the harrow to such a position as to 20 allow the accumulation which has been gathered thereby to be readily removed therefrom.

With these and other objects in view, this invention consists of certain novel constructions, combinations and arrangements of parts as will be fully brought out in the following specification.

In the drawings, Figure 1 is a top plan view of the harrow. Fig. 2 is a side elevation thereof. Fig. 3 is a rear view of the harrow. Fig. 4 is a central section taken along the line 4—4 of Fig. 1. Fig. 5 is a longitudinal section through one of the harrow tooth bars. Fig. 6 is a detail perspective of one of the supporting side members of the main frame of the truck which supports the harrow. Fig. 7 is a detail perspective of a portion of one of the harrow tooth supporting bars showing an operating link 35 connected thereto. Fig. 8 is a transverse section through the operating lever showing the manner of attaching the operating rods to said lever. Fig. 9 is a detail perspective of the quadrant used in connection with the present device. Fig. 10 is a detail perspective of the axle of the harrow. Fig. 11 is a detail perspective of one of the quadrant supporting brackets. Fig. 12 is a section taken on the line 12—12 of Fig. 5.

50 By referring to the drawings, it will be seen that 1 designates the main axle which is supported by means of the wheels 2. A harrow supporting frame 3 is pivotally connected to the axle 1 by means of the pivot pins 4. The harrow supporting frame 3 comprises a pair of parallel bars, and each

of these bars is provided with an offset end 5, which end fits into the socket portion 6 of the central longitudinally-extending frame beams 7 of the harrow. 60

A transversely-extending brace 8 is secured to the side members of the frame 3 and constitutes an efficient means for holding these side members in spaced relation. A quadrant supporting bracket 9 engages the axle 1, and this bracket supports a quadrant 10. An operating lever 11 is pivotally mounted upon the bracket 9 and this operating lever 11 is provided with a spring catch 12 for engaging the quadrant 10 and holding 70 the lever 11 in a set position. A seat 13 of any desired construction is carried by the axle 1 so as to allow the operator to be in a position to have free access to the operating lever 11. 75

A plurality of harrows 14 are carried in front of the frame 3 and the frame 3 is secured to the harrows by having the offset ends 5 engaging the loop portions 6 of the central frame bars 7 of the harrow as above 80 described. A pair of side frame bars 15 is carried by each harrow and each of the bars 7 and 15 is provided with a plurality of apertures 16 through which the harrow bars 17 pass. The harrow bars 17 comprise a 85 substantially U-shaped body through which the harrow teeth 18 extend by having their threaded ends 19 passing through the harrow bars 17. Bolts 20 are placed upon the threaded ends of the teeth 18 for firmly 90 holding the teeth 18 in engagement with the harrow bars 17. The forward ends of the side bars 15 are provided with hook portions 21 which are engaged by the rings 22 of a draft bar 23. This draft bar 23 may be 95 attached to any desired draft means.

The centrally located harrow bar 24 of each harrow carries a pair of segmental runners 25, which runners comprise substantially two-thirds of a circle, and are 100 held in engagement with the bars 24 by means of the transversely-extending bolts 26 passing through the hubs 27 of the runners 25 and through the bars 24.

The transversely-extending bars 17 of each harrow are provided with upwardly-extending links or fingers 28 which are connected to a common operating link 29 for the purpose of rotating the bars 17 and 24 simultaneously. The bar 24 is provided with a long 110 link 30 which is pivotally secured to the connecting link 29, and this link 30 is in

turn secured to one of the operating rods 31, whereby the link 30 may be swung and at the same time rotate the bars 17 with the bar 24. The operating rods 31 converge 5 toward the rear of the machine and have their respective ends secured to the enlarged portion 32 of the operating lever 11 so as to facilitate the rotation of the bars 17 and 24. It, of course, should be understood that 10 as the lever 11 is thrown forwardly to the position shown in dotted lines in Fig. 2, the runners 25 will be rotated and by coming in contact with the ground the harrows 14 will be elevated to the position shown in dotted 15 lines and the harrow tooth supporting bars 17 and 24 will be swung so as to cause the harrow teeth 18 to be rearwardly inclined, thereby allowing the accumulation which has been gathered by the harrow to be removed or dropped therefrom. By again operating the lever 11 to the position shown 20 in full lines, the harrow may assume its normal position and it should be understood that by moving the lever 11 to an adjusted 25 position, the angle of the teeth 18 may be regulated at the will of the driver of the machine or harrow.

From the foregoing description, it will be seen that a very simple and efficient means 30 has been produced for changing the angle of the harrow teeth and at the same time elevating the harrow body without a great amount of effort on the part of the oper-

ator of the machine in view of the fact that the runners 25 will assist the operator in 35 raising the harrow, for as soon as the runners have been thrown into engagement with the ground, the forward movement of the harrow will cause the runners 25 to further rotate thereby assisting the operator in elevating the harrow to the desired position. Merely by throwing the catch 11 into engagement with the quadrant, the runners 25 may be held in a set position.

Having thus described my invention, what 45 is claimed is:—

In a device of the class described the combination with a harrow supporting frame, said supporting frame consisting of a pair of parallel bars, each of said bars 50 having an offset end, a pair of frame beams, socket portions carried at the rear end of said frame beams, harrow bars carried by by said beams, said offset ends fitting into said socket portions, and an axle supporting 55 said supporting frame, runners carried by said harrow bars, and means engaging said runners for bodily raising said harrow bars upwardly.

In testimony whereof I hereunto affix my 60 signature in presence of two witnesses.

WILLIAM S. BALES.
